HONING MANDREL

Joseph Sunnen, Clayton, Mo.

Application February 15, 1949, Serial No. 76,591

4 Claims. (Cl. 51—184.3)

1

This invention relates to mandrels to be used in honing machines of the general type shown in my prior patent No. 2,377,588, patented June 5, 1945, and comprehends a structure particularly adaptable to hones for finishing the interior of relatively small bores. Heretofore it has been customary in the finishing of small bores to use a mandrel carrying a single honing surface as shown for instance in my prior patent No. 2,376,851. However, it is now proposed by means of a novel structure to provide a hone carrying mandrel for use in the finishing of small bores in which a multiplicity of hones may be utilized, suitably spaced and arranged, and so assembled as to retain a substantially rigid assembly.

One of the objects of the present invention is to construct a mandrel in which a multiplicity of diametrically arranged hones are provided for simultaneous adjustment by means of an axially movable wedge.

Another object of the invention is to provide in a mandrel of the type described a structure having the characteristics of a substantially solid body, when the hones and wedges are assembled.

A further object of the invention is to provide a mandrel structure in which there is provided an axial bore for the arrangement and movement of an adjusting wedge, the bore extending throughout the length of the relatively small cylindrical mandrel body and cooperating with wedges arranged in a transverse wedge slot which intersects the axial bore with its central plane at the axis of the bore, so that the hones themselves can be placed in pockets in the mandrel body at each side of the wedge to be solidly and compactly held therein during all positions of adjustment and operation of the device.

Further features of the invention, such as the structure permitting maximum adjustment for the size of the mandrel, without interfering with the strength and rigidity of the assembly, will appear from an inspection of the accompanying claims and drawings, in which latter similar reference characters designate corresponding parts throughout the several views, in which:

Fig. 1 is a longitudinal vertical section through a mandrel, showing the stones and wedges in retracted position;

Fig. 2 is a longitudinal horizontal section of the disclosure of Fig. 1;

2

Fig. 3 is a transverse section taken on line 3—3 of Fig. 1;

Fig. 4 is a side elevation; and

Fig. 5 is an exploded view showing the wedge and the hones.

The mandrel is conventionally constructed of two parts, the first being the chuck head indicated by reference character 1, this chuck head being formed with a stepped bore 2, 2^a, and 2^b for receiving the operating end of the wedge bar 3 and part of the machine operating mechanism. The chuck head 1 is formed with a lateral slot 4 communicating with the bore and in which the relatively wide terminal 5 of the wedge bar 3 is arranged and adapted to travel during the adjustment of the hones. The terminal end 5 of the wedge bar 3 is formed with a hooked end portion 6 for engagement with an actuating mechanism of a honing machine as is conventional in such instances. The hooked terminal portion 5 of the wedge bar 3 is shown as formed of a separate piece of material which is welded or otherwise secured to the inner end of the elongated wedge bar body 3, this structure being mainly for the purpose of convenience in manufacture and to reduce the costs.

The elongated mandrel body 8 is constructed of a steel rod which has been provided with a rectangular axial bore 9 in which the elongated wedge bar 3 is normally arranged, the wedge bar 3 being of dimensions to snugly engage the walls of the rectangular bore 9; the tolerances between the parts being ample to permit manipulation of the wedge bar 3, but preventing lateral or vertical shifting movement when the device is in use. The cylindrical body 8 projects into the outer reduced bore 2^b of the head 1 and is fixed therein by any suitable and expedient means. By forming the head 1 and the mandrel body 8 of separate material it will be apparent to one skilled in the art that a substantial amount of machining and material can be saved in producing the structure in question.

The bore 9 which is generally of rectangular cross-section is of constant area throughout its entire length and extends from within the inner chamber of the head 1 as defined by the bore 2^a throughout the cylindrical body 8. Adjacent the outer end of the mandrel body 8 a transverse

elongated slot of rectangular form is provided, this slot intersecting the bore 9 and being of substantially greater width than the bore 9 and having its longitudinal side walls 10 offset a substantial distance at each side of the walls of slot 9 so as to provide a recess at each side of the wedge bar bore 9 for the reception of hone carriers 12. The transverse slot has its longitudinal center lying in a common plane with the longitudinal center of the bore 9 so that the hone carrying recesses defined by the walls 10 and 11 are of equal size, of rectangular form, and are defined by the longitudinal walls 10, the end walls 11, and when the wedge bar 3 is in position the inner walls of these hone carrier recesses are defined by the side faces of the wedge bar 3. The transverse dimensions of the hone carrier recesses defined by the walls 10 and 11 at each side of the mandrel bore 9 are such as to permit the vertical wall portions 12 of the hone carriers to be seated therein, the inner surfaces 14 of the vertical walls 12 of the hone carriers lying flush with the side walls of the wedge bar 3 when the latter is in position, and the outer faces of the hone carriers continuously contact and lie flush with the elongated walls 10 of the hone carrier recesses, with the end wall portions of the vertical walls of the hone carriers abutting the end walls 11 of the recesses, the fit in each direction being sufficiently accurate as to prevent any shifting of the parts other than in a direction transverse to the movement of the wedge bar 3 when the latter is shifted to secure necessary adjustment of the hones carried by the hone carriers.

In order to operate the hone carriers by means of the wedge bar 3 it will be seen from an inspection of Fig. 5 that the wedge bar 3 is formed at its opposite faces and at its outer ends with the slots 15, the slots at each side being arranged at opposed angles to engage and operate the pair of hone carriers which have similarly arranged ribs 16 projecting from the inner faces of the vertical walls 14 for cooperation with the slots 15.

The peripheral surface of the barrel 8 of the hone body inward of the hone slots is formed at each side with a multiplicity of diagonal parallel slots 18, the groups of slots at each side are all of substantially the same width and depth, the bottom faces 19 being flat and the side walls 20 defining the slots extending vertically with respect to the bottoms thereof. These slots which are provided for the discharge of a coolant may be formed in any suitable manner as by the use of a metal saw, milling machine, or the like. In the illustration shown, the diagonal passages for the coolant are arranged at an angle to the axis of the body and in parallel relation, the groups of slots in each instance traversing approximately one quarter of the circumferential surface of the hone barrel and originating in each instance at a line extending longitudinally of the barrel at approximately the longitudinal center of the hone slot. This arrangement facilitates the movement of the coolant and its discharge from the bore which is being operated upon by the hone assembly.

The individual hone carriers include the vertical elongated wall portions 12 and the horizontal hone carrying flanges 21, the inner faces of the walls 12 and the flanges 21 being at right angles to enable the flange portion 21 to overlie and continuously engage and seat the marginal edge 22 of the wedge bar 3. Obviously the lateral flange 21 of one hone carrier will seat upon the

one edge portion of the wedge bar 3, while the corresponding flange of the other hone carrier will seat upon the opposite edge of the wedge bar. The edges 22 of the wedge bar in each instance lie at right angles to the side walls thereof, thus insuring the proper seating of the faces 21 of the hones. The outer surfaces of the lateral flanges 21 of the hones are machined to present two faces lying at similar acute angles with respect to the inner face of the flange and have secured thereto by an adhesive or otherwise the hone elements 23, the outer faces of which initially may be flat but will normally constitute substantially a continuation of the circumferential surface of the tubular mandrel body as shown in Fig. 3. By this means a maximum honing area will be presented to the work and this working area will properly distribute the inherent forces created as a result of the honing operation due to the frictional engagement between the hones 23 and the wall of the bore against which it may be operating. It will be further noted by an inspection of Fig. 3 that the thickness of the wedge bar 3 and the thickness 25 of the vertical walls 12 of the two hone carriers constitute a measurement, with suitable tolerances for adjustment, corresponding to the distance between the transverse walls of the hone slot 10 so that in assembly these parts are prevented from having play in any direction, but on the contrary present substantially a solid working element for accomplishing the desired finishing operation in a bore. The solid structure provided by the assembly eliminates chattering and 30 consequently marring of the surfaces being finished. Also the transverse arrangement of the hones with respect to the associated parts provides the required passageways for the movement of a coolant to all of the area being honed, thus 35 insuring against undesirable heating.

I claim:

1. In a honing mandrel for use in finishing small bores in metal structures, a body including an enlarged, hollow head portion, a relatively slender mandrel shaft extending concentrically from said body, said shaft being formed throughout with a straight uniform axial bore of rectangular cross section, a relatively wide transverse hone carrier slot extending through the outer end portion of the shaft, and intersecting said bore, the width of the slot being such as to provide lateral hone carrier receiving recesses at each side of said axial bore, an elongated wedge bar of rectangular cross section snugly arranged in said bore for longitudinal movement, said wedge bar being formed with parallel angularly extending wedge slots at each side, and hone carrier elements having portions snugly seating in said recesses and constructed and arranged for radial movement therein, said hone carriers being formed with parallel angularly arranged wedge projections normally extending into the wedge slots of said wedge bars, and including angular hone carrying portions overlying the edge portions of said wedge bar.

2. The substance of claim 1 characterized in that the inner faces of the hone carriers are in a common plane with the side faces of the bore and abut the side faces of the wedge bar.

3. The substance of claim 1 characterized in that the hone carrying elements are positioned for radial adjustment in the hone recesses by the side walls of the wedge bar which forms the inner guide for the hone, and include hone sup-

porting projections which overlie the opposite sides of the wedge bar.

4. In a hone mandrel, a mandrel shaft having a longitudinal axial bore formed with parallel, spaced walls, a slot extending transversely through the bar and intersecting said bore to provide hone carrier recesses offset laterally from said axial bore, a wedge bar of uniform cross section extending through the mandrel bore and lying flush against the parallel walls thereof, said wedge bar having at each side thereof angularly disposed slots, and hone carriers in said hone slots at each side of the bar having portions engaging said slots, said carriers being of L-form and the leg of each carrier having its inner face 15 overlying the edges of the wedge bar, and sup-

porting elongated radially extending hone elements.

JOSEPH SUNNEN.
